UNITED STATES PATENT OFFICE

106,588

DESIGN FOR A STOCKING

George F. Aberle, Elkins Park, Pa., assignor to H. C. Aberle Co., Philadelphia, Pa., a corporation of Pennsylvania

Application September 10, 1937, Serial No. 71,558

Term of patent 7 years

To all whom it may concern:

Be it known that I, George F. Aberle, a citizen of the United States and a resident of Elkins Park, county of Montgomery, State of Pennsylvania,
have invented a new, original, and ornamental Design for a Stocking, of which the following is a specification; reference being had to the accompanying drawing, forming part thereof, in which:

Figure 1 is a side view of a stocking showing my new design; and

Fig. 2 is an enlarged detached view showing the details of the lace.

I claim:

The ornamental design for a stocking, substantially as shown.

GEORGE F. ABERLE.
